CLAIM

The ornamental design for an automated assay system, as shown and described.

DESCRIPTION

FIG. 1 is a perspective view of the automated assay system showing a our new and ornamental design;

FIG. 2 is a front view thereof;

FIG. 3 is a back view thereof;

FIG. 4 is a side view thereof;

FIG. 5 is an opposite side view thereof; and,

FIG. 6 a top view thereof.

(Continued)

The portions of the automated assay system shown in broken lines shown in the figures attached hereto form no part of the claimed design.
